Inventor

T. J. Moss,

UNITED STATES PATENT OFFICE.

THOMAS J. MOSS, OF ST. LOUIS, MISSOURI.

CHOCK.

1,035,381.

Specification of Letters Patent. Patented Aug. 13, 1912.

Application filed April 5, 1912. Serial No. 688,818.

To all whom it may concern:

Be it known that I, THOMAS J. Moss, a citizen of the United States, residing at St. Louis, State of Missouri, have invented certain new and useful Improvements in Chocks, of which the following is a specification, reference being had to the accompanying drawings.

This invention comprehends certain new and useful improvements in accessories for automobiles and similar vehicles, and relates particularly to an improved chock or block for motor cars designed for use in holding the cars stationary while repairing a tire or in other situations where it is impracticable to set the emergency brakes.

The invention has for its primary object a simple, durable and efficient construction of device of this character, the parts of which are so arranged that they may be cheaply manufactured and readily assembled and disassembled, the device being collapsible so that it may be easily carried in the tool box where it will take up very little room. And the invention also aims to generally improve devices of this class and to render them more useful and commercially desirable.

With these and other objects in view, as will more fully appear as the description proceeds, the invention consists in certain constructions, arrangements and combinations of the parts that I shall hereinafter fully describe and claim.

For a full understanding of the invention, reference is to be had to the following description and accompanying drawing, in which,

Figure 1 is a longitudinal sectional view of one form or embodiment of my invention. Fig. 2 is an end view thereof. Fig. 3 is a detail perspective view of the brace plate or strut employed with the modification illustrated in Figs. 1 and 2. Fig. 4 is a sectional view of another view of the device, and, Fig. 5 is an end view thereof.

Corresponding and like parts are referred to in the following description and designated in the accompanying drawing by like reference characters.

In that embodiment of the invention illustrated in Fig. 1, the device comprises two plates designated 1 and 2, the same being preferably formed of sheet metal and being hingedly or otherwise movably connected together at one edge, as indicated at

3. Each plate is formed at the middle with any desired number of apertures or slots 4 which are designed to receive and detachably hold lugs 5 that are formed on two side edges of a substantially triangular brace plate or strut 6, whereby when said brace plate is inserted in between the plates 1 and 2 and its lugs 5 engaged in the slots 4, the said plates will be held in angular relation to each other and may effectively serve as a wedge or chock against a wheel of the automobile.

In that embodiment of my invention illustrated in Fig. 4, the brace plate, there designated 6*, is hingedly connected to one of the plates and is formed with lugs 5* designed for engagement in slots 4* in the other plate. In other respects, this device is like that illustrated in Fig. 1.

From the foregoing description in connection with the accompanying drawing, the operation of my improved chock will be apparent. By hingedly connecting the plates 1 and 2 together and by hingedly connecting the brace plate to one of the plates so as to swing laterally thereon, or by forming the said brace plate on two edges with the lugs before mentioned, it is obvious that the device may be folded, one part upon another, and carried in a very compact condition in a tool box or other receptacle. When the device is required for use, it may be easily set up, either by inserting the brace plate 6 in between the plates 1 and 2 and engaging the lugs 5 in the slots 4 as regards that embodiment of the invention illustrated in Fig. 1, or may be set up by opening plates 1 and 2 and swinging the brace plate 6 to a right angular position relative to the plate 1 and then inserting the lugs 5* into the slots 4*.

While the accompanying drawing illustrates what I believe to be the preferred embodiment of my invention, it is to be understood that the invention is not limited thereto, but that various changes may be made in the construction, arrangement and proportions of the parts without departing from the scope of the invention, as defined in the appended claims.

What I claim is:

1. A chock for vehicle wheels, comprising sheet metal plates movably connected together at one edge, and a sheet metal brace plate of triangular formation designed for insertion in between the first named plates

the brace plate and first named plate being formed with coacting means for connecting the brace plate and the first named plate whereby to hold one of the first named plates in an angular relation to the other first named plate.

2. A chock for vehicle wheels, consisting of sheet metal plates hingedly connected together at one edge, one of said plates being formed with slots, a brace formed with edge lugs adapted to engage said slots, and means for connecting said brace with the other plate.

3. A chock for vehicle wheels, consisting

of sheet metal plates hingedly connected together on one edge, said plates being formed intermediate of their side edges and in line with each other with slots, and a triangular brace plate designed for insertion in between the hinged plates and formed with edge lugs adapted to engage in said slots.

In testimony whereof I hereunto affix my signature in the presence of two witnesses.

THOMAS J. MOSS.
